UNITED STATES PATENT OFFICE.

DANIEL C. BELTZ, OF BIRMINGHAM, ALABAMA.

DESIGN FOR A TURPENTINE-BOX.

SPECIFICATION forming part of Design No. 33,542, dated November 13, 1900.

Application filed October 18, 1900. Serial No. 33,520. Term of patent 14 years.

To all whom it may concern:

Be it known that I, DANIEL C. BELTZ, a citizen of the United States, residing at Birmingham, in the county of Jefferson and State of Alabama, have invented and produced a new and original Design for a Turpentine-Box, of which the following is a specification.

The invention relates to a new and original design for turpentine-boxes; and it has for its object to provide a design of this character which will be both ornamental and useful.

The leading feature of the design consists in the design forming the subject-matter of the accompanying illustration.

In the drawings, Figure 1 is a perspective view of a turpentine-box, showing my new and original design. Fig. 2 is a front elevation of the same. Fig. 3 is a vertical sectional view.

Referring to the drawings, 1 designates a turpentine-box provided with a curved front 2 and having an approximately semicircular lower edge 3, extending from the bottom of the receptacle to the upper edges of the front, at the sides of the box, as clearly illustrated in Fig. 2 of the accompanying drawings. The back 4 of the box is provided with a lower

vertical portion having a lower curved edge to conform to the configuration of the bottom of the box and provided with a centrally depending ear 5, and it extends above the front of the box and is provided with an inclined upper portion 6. The inclined upper portion 6, which is arranged at an obtuse angle to the lower vertical portion, is provided at opposite sides with longitudinal flanges 7, and it has an approximately semicircular upper edge 8, terminating short of the side edges of the portion 6 and connected therewith by short transversely-disposed straight edges 8^a. The depending ear 5 is provided with an opening, and the tapering side extensions 9, formed by the curved edge 8 of the inclined portion 6, are also provided with openings.

What is claimed is—

The design for a turpentine-box, herein shown and described.

In testimony that I claim the foregoing as my own I have hereto affixed my signature in the presence of two witnesses.

DANIEL C. BELTZ.
